(57) **CLAIM**

We claim the ornamental design for a hand-held electronic device cover, as shown and described.

DESCRIPTION

FIG. 1 is a front perspective view of a hand-held electronic device cover;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines that show the outermost periphery of non-claimed features represent the boundaries of the claimed design. All other broken lines are directed to environment and are for illustrative Purposes only. The broken lines and the unshaded regions that are bounded by broken lines form no part of the claimed design.
